(57) **CLAIM**

The ornamental design for a mid-sole cleat, as shown and described.

DESCRIPTION

FIG. 1 is a perspective view of a mid-sole cleat;

FIG. 2 is a top view thereof;

FIG. 3 is a side view thereof;

FIG. 4 is a bottom view thereof;

FIG. 5 is a front view thereof; and

FIG. 6 is a back view thereof.

FIG. 7 is a perspective view of another embodiment of a mid-sole cleat;

FIG. 8 is a top view thereof;

FIG. 9 is a side view thereof;

FIG. 10 is a bottom view thereof;

FIG. 11 is a front view thereof; and,

FIG. 12 is a back view thereof.

(Continued)

The dashed lines show portions of the mid-sole cleat that form no part of the embodiment in which they are shown.
